UNITED STATES PATENT OFFICE.

RICHARD WATSON FOX, OF ALTOONA, PENNSYLVANIA.

DRAW-BAR RIGGING.

SPECIFICATION forming part of Letters Patent No. 714,689, dated December 2, 1902.

Application filed February 8, 1902. Serial No. 93,167. (No model.)

To all whom it may concern:

Be it known that I, RICHARD WATSON FOX, a citizen of the United States, residing at Altoona, in the county of Blair and State of Pennsylvania, have invented a new and useful Improvement in Draw-Bar Rigging, of which the following is a specification.

This invention is an improved draw-bar rigging, the object of the invention being to provide a much simpler and stronger form of rigging than those now in use, and while my invention is particularly adapted for freight and heavy-draft cars it can be applied with equal facility to passenger-coaches.

One object of the invention is to provide a draw-bar rigging in which the parts shall be so constructed and arranged that in case any or all of them should break it will be impossible for them to fall beneath the car or interfere with its travel.

Another object of the invention is to provide a rigging which can be quickly and easily adjusted for the purpose of replacing any of the parts.

With these various objects in view the invention consists, essentially, in arranging two bearing-plates in parallel order beneath the timbers of the car, said bearing-plates being slotted horizontally and also provided with apertures, arranging a draft-bar between the said plates, said draft-bar having laterally-projecting studs adapted to slide in the horizontal slots, a bearing-block arranged also between the plates and having laterally-projecting studs adapted to rest in the apertures in the plates, said block having a central bore through which the rearwardly-projecting shank of the draw-bar passes, said shank being threaded at its rear end for the purpose of receiving the jam-nuts, a draw-spring surrounding the shank and bearing against the rear face of the bearing-block and a cushion-spring interposed between the draw-bar and forward side of the bearing-block, the forward end of the draw-bar being shaped to receive the rear end of the draw-head.

The invention consists also in certain details of construction and novelties of combination hereinafter fully described, and pointed out in the claims.

In the drawings forming part of this specification, Figure 1 is a view showing the practi-

cal application of my invention, the underside of a car being shown in perspective. Fig. 2 is a longitudinal sectional view, the draw-bar 55 shank, draw-spring, and jam-nuts being shown in elevation. Fig. 3 is a sectional plan view. Fig. 4 is a transverse section on the line 4-4 of Fig. 3. Fig. 5 is a detail perspective view of one of the bearing-plates. Fig. 6 is a detail perspective view of the draw-bar and the rearwardly-projecting shank. Fig. 7 is a detail perspective view of the combined guide and bearing-block. Fig. 8 is a perspective view illustrating the rear end of the draw-head. Fig. 9 is a sectional perspective view illustrating the forward end of the draw-bar, into which the rear end of the draw-head fits. Figs. 10, 11, and 12 show my invention adapted to the Janney coupler.

In constructing a draw-bar rigging in accordance with my invention I employ two bearing plates or castings A, having the upper and lower flanges A', through which the fastening-bolts A² are passed and by means 75 of which the bearing plates or castings are securely fastened to the bottom timbers of the car. These plates or castings A are arranged longitudinally beneath the car and in parallel order, as most clearly shown, and the bottom plate B is securely connected to the under sides of said plates or castings, the bolts A² serving to fasten the bottom plate to the said bearing plates or castings, as most clearly shown in Figs. 2 and 3. The bearing plates 80 or castings A are formed with horizontal slots A³ adjacent to their forward ends and circular apertures A⁴ adjacent to their rear ends, the said slots and openings being reinforced by means of outwardly-projecting flanges A⁵, 90 said flanges forming broad bearings for the parts hereinafter referred to. The draft-bar C is arranged between the bearing plates or castings A and is provided with laterally-projecting studs C', which are adapted to work 95 in the horizontal slots A³ and bear upon the flanges A⁵. The draft-bar C is also formed with a rearwardly-projecting shank or bar C², the rear end of which is threaded, as most clearly shown at C³, and the forward end of the draw-bar is formed with a T-shaped socket C⁴, into which fits the T-shaped end D⁴ of the draw-head D, said end D⁴ being wedge-shaped, as shown, in order to interlock with the

socket C⁴, which is made tapering, as most clearly shown in Figs. 2 and 9. A combined guide and bearing-block E is arranged also between the bearing plates and castings A, 5 said block E having laterally-projecting studs E', which are adapted to fit into the apertures A⁴ and bear upon the surrounding flange. This block E is also formed with a central bore E², through which the shank C² of the 10 draw-bar passes. A draft-spring F surrounds the shank or rod C², its forward end bearing against the rear end of the block E, its rear end being held in place by means of a plate F', which is secured upon the threaded end 15 of the shank or bar by means of the jam-nuts F² and F³, said jam-nuts being screwed upon the threaded ends C³. This draft-spring F receives the initial strain which is thrown upon the block E, and inasmuch as the said block 20 is very strong and also provided with stout studs E', which rest upon reinforced flanges A⁵, it will be readily understood that my form of rigging is particularly adapted for receiving severe strains, such as are caused by pulling heavy loads or ascending steep grades. 25 A cushion-spring G surrounds the shank or rod C² between the rear end of the draw-bar C and the forward end of the guide or bearing-block E, the purpose of said spring being 30 to take up the jar incidental to coupling when two draw-heads are brought together. A stout eyebolt H is inserted in the bottom of the draw-bar C, adjacent to the forward end, for the purpose of connecting a chain or other 35 form of coupling device thereto in case the draw-head should become damaged, and in order to permit the longitudinal movement of the draw-bar bearing said eyebolt I provide a longitudinal slot H' in the bottom plate 40 B and in which the said eyebolt works during the longitudinal movement of the draw-bar. In case the draw-head should become damaged and it should become necessary to attach another one the jam-nuts are loosened 45 sufficiently to permit the forward end of the draw-bar to protrude beyond the bearing-plates, and the draw-bar can then be quickly and easily attached or detached, as desired. In case the draw-bar should become damaged 50 it can be quickly and easily removed and another one inserted, and inasmuch as each and every part of my rigging is supported above the bottom plate B and also formed with lateral bearings it will be seen that it will be impossible for any of the parts to fall beneath 55 the car.

In Figs. 10, 11, and 12 I have shown my invention adapted to the ordinary form of Janney coupler, and in such construction the 60 draw-head D' is provided with rearwardly-projecting pivot-ears D², which rest above and below the forwardly-projecting portion D³ of the draft-bar, said portions being connected by means of a bolt B⁵. The end of the forwardly-projecting portion D³ is bifurcated, as 65 shown at D⁶, and secured in such bifurcation are the diverging springs D⁷, which project

forwardly into the draw-head and serve to normally hold the head in its proper position for coupling; but the elasticity of these 70 springs permits the head to turn upon the bolt when rounding curves. The general arrangement of suspending or supporting the draft-bar is identically the same as that shown in Figs. 1 to 9, inclusive. 75

Having thus fully described my invention, what I claim as new, and desire to secure by Letters Patent, is—

1. In a draw-bar rigging, the combination 80 with the bearing plates or guides secured to the under side of the car arranged parallel with each other, and having longitudinal slots therein; of a combined bearing-block and guide pivoted in said bearing-plates, and having a circular hole or opening there- 85 through, a draw-bar having a rearwardly-projecting shank passing through and guided by said circular opening in said bearing-block, lugs thereon sliding in said longitudinal slots in said bearing-plates, and a draw- 90 head or coupling member at one end thereof; and a draft-sustaining spring coiled around said shank and interposed between said bearing-block and a shoulder or collar on said shank, substantially as described. 95

2. In a draw-bar rigging, the combination 100 with the bearing plates or guides secured to the under side of the car arranged parallel with each other, and having longitudinal slots therein, of a combined bearing-block and guide pivoted in said bearing-plates, and having a circular hole or opening there- 105 through, a draw-bar having a rearwardly-projecting shank passing through and guided by said circular opening in said bearing-block, lugs thereon sliding in said longitudinal slots in said bearing-plates, and a draw- 110 head or coupling member at one end thereof, a draft-sustaining spring coiled around said shank and interposed between said bearing-block and a shoulder or collar on said shank, and a cushion-spring interposed between 115 said draw-bar and bearing-block, substantially as described.

3. In a draw-bar rigging, the combination 115 with the bearing plates or guides secured to the under side of the car arranged parallel with each other, and having longitudinal slots therein, of a combined bearing-block and guide pivoted in said bearing-plates, and having a circular hole or opening there- 120 through, a draw-bar having a rearwardly-projecting shank passing through and guided by said circular opening in said bearing-block, lugs thereon sliding in said longitudinal slots 125 in said bearing-plates, and a T-shaped slot or socket in the forward end thereof, a draw- 130 head or coupling having a T-shaped rear end adapted to engage in said slot or socket in the draw-bar, and a draft-sustaining spring coiled around said shank and interposed between 135 said bearing-block and a shoulder or collar on said shank, substantially as described.

4. In a draw-bar rigging the combination with the bearing plates or guides secured to the under side of the car arranged parallel with each other, and having longitudinal slots therein, of a combined bearing-block and guide pivoted in said bearing-plates and having a circular hole or opening therethrough, a draw-bar having a rearwardly-projecting shank passing through and guided by said circular opening in said bearing-block, lugs thereon sliding in said longitudinal slots in said bearing-plates, and a T-shaped slot or socket in the forward end thereof, a draw-head or coupling having a T-shaped rear end, adapted to engage in said slot or socket in the draw-bar, a draft-sustaining spring coiled around said shank and interposed between said bearing-block, and a shoulder or collar on said shank, and a cushion-spring interposed between said draw-bar and bearing-block, substantially as described.

5. In a draw-bar rigging, the combination

with the bearing plates or guides secured to the under side of the car, arranged parallel with each other, and having longitudinal slots therein, of a combined bearing-block and guide pivoted in said bearing-plates, and having a circular opening or hole therethrough, a draw-bar having a rearwardly-projecting shank passing through and guided by said circular opening in said bearing-block, the end of said shank being screw-threaded and having jam-nuts thereon, lugs on said draw-bar, sliding in said longitudinal slots in said bearing-plates, and a draw-head or coupling member at one end of said draw-bar, and a draft-sustaining spring coiled around said shank and interposed between said bearing-block and the jam-nuts on said shank, substantially as described.
